UNITED STATES PATENT OFFICE.

HENRY Y. HOOPER, OF NEWARK, NEW JERSEY.

RADIATOR CAP.

Application filed February 8, 1924. Serial No. 691,357.

This invention relates to caps for the filler-necks of automobile radiators and more particularly to caps of this type having associated therewith a temperature indicating device whereby a visual indication of the temperature of the water in the radiator is afforded.

The invention seeks to provide a cap for the filler-neck of the radiator found on the 10 Ford automobile which shall have operatively associated therewith what is known in the trade as a Boyce motometer and which can be readily and conveniently attached without the aid of special tools or experience, but which, once attached cannot be 15 normally removed, ready means being afforded for filling the radiator without removal of the cap. Accordingly the cap is so formed as to be readily slipped over the 20 filler-neck and is provided with devices permitting the application of the cap but preventing its removal once it is in place.

The invention also seeks to provide means whereby the radiator may be conveniently 25 filled without completely disassociating the motometer from the cap. To this end the aperture in the cap through which the radiator is to be filled is provided with a hinged cover which has the motometer permanently 30 secured thereto and which is adapted to be releasably retained in closing relation with the cap.

These and other objects of the invention will be apparent from the following detailed 35 description of the accompanying drawings illustrating a preferred embodiment of the invention in which:

Figure 1 is a view in front elevation showing the filler-neck of an automobile radiator provided with a cap according to the 40 present invention.

Figure 2 is a view, partly in section and partly in elevation taken in the plane indicated by the broken line 2-2 in Figure 1.

The filler-neck α is shown in Figure 1 as 45 permanently carried with an automobile radiator, the upper portion of which is indicated in outline at α' . In Figure 2 the upper portion of the filler-neck is shown in 50 elevation and is formed of gradually narrowing diameter for a substantial portion of its length while the extreme upper portion α^2 of the neck is of increased diameter to form the shoulder α^3 . As furnished with a 55 Ford automobile, the upper portion α^2 of the filler-neck is interiorly threaded to re-

ceive a closing plug. Such a plug has been found inconvenient however, since it is easily lost and moreover does not afford a suitable base for a temperature indicating device 60 such as a motometer. It is proposed, therefore, to substitute for the standard threaded plug furnished with Ford cars a cap comprised principally of a substantially cylindrical cap element β which is adapted to 65 be slipped over the filler-neck α and held against removal therefrom. To this end the interior wall is formed with a plurality of recesses β' having leaf springs β^2 secured therein in any convenient manner, as by 70 rivets β^3 , and so formed as to normally extend outward, as shown in Figure 2, to engage the shoulder α^3 on the filler-neck. It will be apparent that when the cap is being slipped on over the neck the upper portion 75 α^2 will force the springs β^2 back into the recesses to permit the passage of that portion of the filler-neck but that after the cap is in place the springs will spring out of the recess to engage the shoulder and prevent 80 withdrawal of the cap thereafter. Thus a permanent junction between the cap and filler-neck can be obtained by the most inexperienced and this junction is one which requires no tools to effect. The cylindrical 85 portion β is most conveniently provided with an interiorly projecting flange β^4 adapted to rest upon the upper edge of the filler-neck. To form a tight joint between the cap and filler-neck a gasket c of fibre or 90 yielding material may be provided therebetween.

The interiorly extending flange β^4 also serves as a seat for the cover d closing the open end of the cylindrical portion β which 95 cover is hinged at the pivot d' whereby it may be swung in the direction of the arrow about the pivot as an axis to uncover the opening in the filler-neck through which the radiator is to be filled with water. In closing 100 position the cover is secured by means of a spring latch β^5 secured as by a rivet β^6 in a recess in the cap β and normally extending inwardly as illustrated to yieldingly engage a lip d^2 on the cover. It is preferred to strike out from latch β^5 a lip β^7 105 which normally lies over the lip d^2 on the cover to further assist in retaining it in closing position.

The visual temperature indicating device 110 designated in general at e may be of standard construction and is permanently car-

ried by the cover *d* as will be understood. It will thus be seen that the motometer is secured to the cap in a manner which renders it practically impossible of removal without destroying the hinge of the cover by means of tools and is therefore unlikely to be stolen in the ordinary course of events.

The cap as a whole is neat in appearance, 10 simple in construction and its permanent application to the filler-neck of radiators of the contemplated type is easy of accomplishment. Various modifications may be made in the manner of securing the cap to 15 the filler-neck and in closing the filling opening as well as in the type of temperature indicating device associated therewith without departing from the spirit and scope 20 of the invention and no limitation is intended except as indicated in the accompanying claims.

What I claim is:

1. The combination with an automobile radiator filler-neck formed with a shoulder, 25 of a cap including a cylindrical portion

whereof the inner wall is formed with a recess, a resilient member carried in the recess for engagement with the shoulder, a cover hinged at one end of the cylindrical portion, means carried by the cylindrical portion to releasably engage the cover and a temperature indicating device carried by the cover.

2. As an article of manufacture, a radiator cap to be locked onto an automobile radiator having a filler-neck formed with a shouldered portion, comprising a cylindrical portion having the inner wall formed with a plurality of recesses at its lower end and a recess at its upper end, a plurality of resilient fingers carried in the lower recesses to engage the shoulder of the filler-neck, a cover on the upper end of the cylindrical portion, and a resilient catch carried in the upper recess to normally engage the cover.

This specification signed this 18th day of January, A. D. 1924.

HENRY Y. HOOPER.
